CLAIM

The ornamental design for a fiber optics connector, as shown and described.

DESCRIPTION

FIG. 1 is a front and right perspective view of the fiber optics connector;

FIG. 2 is a front and left perspective view of the fiber optics connector shown in FIG. 1;

FIG. 3 is a front view of the fiber optics connector shown in FIG. 1;

FIG. 4 is a right side view of the fiber optics connector shown in FIG. 1;

FIG. 5 is a left side view of the fiber optics connector shown in FIG. 1;

FIG. 6 is a rear view of the fiber optics connector shown in FIG. 1;

FIG. 7 is a top view of the fiber optics connector shown in FIG. 1; and,

FIG. 8 is a bottom view of the fiber optics connector shown in FIG. 1.

The broken line showing on the drawing disclosure is for illustrative purposes only and forms no part of the claimed design.
